(57) **CLAIM**

The ornamental design for a media player, as shown and described.

DESCRIPTION

FIG. 1 is a top perspective view of an interface showing our new design;

FIG. 2 is a top view thereof;

FIG. 3 is a front view thereof;

FIG. 4 is a rear view thereof;

FIG. 5 is a right side view thereof;

FIG. 6 is a left side view thereof;

FIG. 7 is a bottom view thereof; and,

FIG. 8 is a top perspective view of the media player of FIG. 1 in an open state.

The broken lines immediately adjacent to the shaded areas form unclaimed boundaries of the design. The unshaded interior regions visible in FIG. 8 are for environmental purposes only and form no part of the claimed design. The broken line showing of the curved lines on the front surface, the ports on the rear surface, the rectangular and ovular features on the sides, and the remainder of the media player is for environmental purposes only and forms no part of the claimed design.
